[57] **CLAIM**

The ornamental design for a fluid access port for medical container, as shown and described.

DESCRIPTION

FIG. 1 is a perspective view of a fluid access port for medical container, showing our new design, the broken line is for illustrative purposes only and forms no part of the claimed design;

FIG. 2 is a top plan view of the medical container;

FIG. 3 is a side elevational view thereof, the opposite side elevational view being identical thereof;

FIG. 4 is a bottom plan view thereof, and;

FIG. 5 is an end elevational view thereof, the opposite end elevational view being identical thereto.

FIG. 1

FIG. 2

FIG. 3

FIG. 4

FIG. 5
